Company, Kalamazoo, Mich., a corporation of
Michigan

No Drawing. Application August 19, 1948,
Serial No. 45,198

2 Claims. (Cl. 167—51.5)

1

This invention relates to a pharmaceutical preparation containing, as active ingredients, an absorbable sulfonamide in combination with folic acid.

It is well known that the administration of sulfonamides causes extensive changes in the blood picture. These changes, such as granulocytopenia and anemia, as well as others, have been grouped together under the general term of blood dyscrasia. The appearance of blood dyscrasia following the administration of sulfonamide drugs constitutes one of the most important undesirable side effects of such therapy, making it necessary to maintain careful clinical observation of the patient's blood. The blood changes may even be of such an extensive and severe nature as to demand cessation of sulfonamide therapy before such is desirable. After an abnormal blood picture has once appeared, it is extremely difficult to restore it again to normal. This is particularly true when the patient is suffering from a serious disorder other than blood dyscrasia, the correction of which may be very difficult without the use of sulfonamides. It is also believed that the presence of granulocytes in the blood cells is essential for the destruction of infecting bacteria, as the sulfonamides are considered merely to prevent multiplication of, and not actually to kill, those organisms already present, and the reduction in number of these granulocytes by sulfonamide therapy presents a further complication in effecting restoration of the patient's health.

Curative measures of any sort are most undesirable as the incidence of total or acute incapacitation upon onset of the blood dyscrasias is very high, and only a limited percent of the patients treated after symptoms of blood dyscrasia have once appeared are capable of complete or ready recovery even over a lengthy period of time. An increased mortality or prolonged incapacity in such cases appears to be unavoidable. It is thus not only impractical but also mortally dangerous to attempt corrective measures for the sulfonamide-produced blood dyscrasia, e. g., administration of corrective agents after soluble sulfonamide blood effects have set in. It is further true that such corrections as can be made are only possible upon discontinuation of the sulfonamide therapy, thus leaving the patient in a particularly helpless position if his infection has not yet been corrected and sulfonamide treatment is vitally in order, or susceptible to a further onslaught of the infection if incomplete recovery has been made and recuperative sulfonamide therapy is advis-

2

able. Obviously, corrective therapy is not a satisfactory procedure.

The sulfonamide drugs can be divided into those whose therapeutic effect is not due to their absorption from the stomach or intestines, acting directly upon the bacterial flora of the intestine, and those whose therapeutic effectiveness is dependent upon an effective concentration in the blood, namely, the absorbable or soluble sulfonamides. It is known that insoluble sulfonamides which are not absorbed from the intestine destroy the normal bacterial flora of the intestine, and that, by such destruction, the synthesis of certain substances needed by the body is prevented. Among the substances, the synthesis of which may thus be prevented, are certain members of the vitamin B complex, in particular folic acid and its conjugates. However, the soluble sulfonamides, the therapeutic effectiveness of which is due to a high blood level, contrastingly do not reduce the bacterial flora of the intestine to an extent such as to interfere with body synthesis, and dyscrasia, appearing upon soluble sulfonamide therapy would not appear to be due to inhibition of folic acid production by the body.

Therefore, the curative administration of folic acid after soluble sulfonamide therapy in an attempt to eliminate the blood dyscrasia effects of the sulfonamide treatment is not only unsuggested, since soluble sulfonamides do not decrease the amount of folic acid synthesized by the body, but would also be inadequate even if some beneficial result were obtained.

The use of preventive folic acid therapy has appeared impossible up to the present time, for it is known that folic acid is substituted para-aminobenzoic acid which, upon subjection to physiologic action of the body, is believed to dismutate into its moieties, including the para-aminobenzoic acid moiety. Para-aminobenzoic acid has the capacity of preventing blood dyscrasia when administered together with soluble sulfonamides, but unfortunately renders the sulfonamide entirely or very nearly completely ineffective bacteriostatically or bactericidally, and hence the combination of soluble sulfonamides and para-aminobenzoic acid, while eliminating the blood dyscrasia effect of the sulfonamide treatment, also eliminates completely any beneficial effects of the sulfonamide. No reason is apparent why the same effect should not be produced by a substituted para-aminobenzoic acid, in which case the combination would also be without therapeutic utility.

It was totally unexpected to us that the com-

bination of folic acid, a substituted para-amino-benzoic acid, and a soluble sulfonamide should not only prevent the blood dyscrasia but also allow unaltered effectiveness of the soluble sulfonamide.

It is therefore an object of the present invention to provide a preparation which prevents the appearance of blood dyscrasia, in animals and man, due to the administration of soluble sulfonamides. It is an additional object of this invention to provide a soluble sulfonamide preparation which prevents the appearance of blood dyscrasia without interfering with the therapeutic effectiveness of the sulfonamide. Other objects of the invention will become apparent hereinafter.

It has now been found that the simultaneous administration of suitable dosage of folic acid together with a soluble sulfonamide surprisingly results in no decrease in the therapeutic efficiency of the sulfonamide in the blood stream but does prevent the appearance of an abnormal blood picture. The simultaneous administration of folic acid with soluble sulfonamides moreover counteracts to a great extent the retardation of the growth rate of young animals produced by sulfonamides alone. Obviously such finding has great importance.

According to the present invention, the folic acid which is administered simultaneously with the soluble sulfonamide drug may be that contained in a naturally occurring folic-acid-containing material such as aqueous liver extract or dried yeast, or may be synthetic or purified material, or a physiologically active derivative of folic acid. A preferred embodiment of this invention contemplates employment of a highly purified or synthetic folic acid or a physiologically active derivative thereof, either wholly or at least in part.

It is of importance that at least 50 gammas (0.05 milligram) of folic acid or its equivalent as a derivative per gram of sulfonamides be administered simultaneously with the sulfonamide. More may be administered, the maximum being that quantity which, in combination with the total daily dose of the soluble sulfonamide, will furnish for the species of animal to be treated, the daily requirement for folic acid of that particular species of animal under sulfonamide therapy. A representative formula which may be used in the practice of the present invention consists of:

	Mg.
Sulfadiazine	167
Sulfamerazine	167
Dried aqueous liver extract	167
Folic acid	0.25

The dried aqueous liver represents three grams of fresh liver. In addition such excipients, binders, and lubricants may be used as to enable this mixture to be made into a compressed tablet. Alternatively the formula may be used as a powder, although such is not a preferred form of administration. The composition may also be administered in the form of a syrup. These products are useful for oral administration in the treatment of animals, such as dogs and cats, as well as in the treatment of man.

The following examples are illustrative only and are not to be construed as limiting:

Example 1

Twenty-eight-day old weanling white rats of random sex, 45-50 grams in weight, were placed on a basal purified diet composed of 72 percent

sucrose, 18 percent casein (Labco, vitamin-free), three percent cottonseed oil, two percent cod liver oil, four percent salt, 0.1 percent choline chloride, 0.1 percent inositol, and 200 gamma percent of

5 vitamin K (dissolved in the cod liver oil). Daily supplements of crystalline vitamins included; thiamine hydrochloride, 200 gammas; riboflavin, 100 gammas; pyridoxine hydrochloride, 100 gammas; calcium d-pantothenate, 200 gammas; nicotinamide, 500 gammas; and biotin, 1 gamma. When fed on this basal diet for 35 days, 10 of 10 experimental animals survived and gained an average of 58 grams. The blood picture was as follows:

15 White cells, 9,700 per cubic millimeter
Granulocytes, 1,130 per cubic millimeter
Red cells, 8,000,000 per cubic millimeter
Hemoglobin, 14.2 grams per 100 milliliter
20 Hematocrit 42.0 volume percent

Example 2

One percent of sulfathiazole was added to the basal diet of Example 1. At the end of 36 days, 25 seven of the original ten experimental animals had survived, those surviving having gained an average of 18 grams per animal. An examination of the blood of these animals showed on the average:

30 White cells 7,500 per cubic millimeter
Granulocytes, 80 per cubic millimeter
Red cells, 7,500,000 per cubic millimeter
Hemoglobin, 11.9 grams per 100 milliliter
35 Hematocrit 41.0 volume percent

Example 2A

One hundred gammas of folic acid per gram of sulfonamide was added to the basal diet containing one percent sulfathiazole used in Example 2, and this supplemental diet fed to ten animals. At the end of 36 days seven of the animals had survived, those surviving having gained on the average of 30 grams each. The blood picture was as follows:

40 White cells, 14,300 per cubic millimeter
Granulocytes, 1,860 per cubic millimeter
Red cells, 8,500,000 per cubic millimeter
Hemoglobin, 13.3 grams per 100 milliliter
45 Hematocrit, 44.0 volume percent

Example 2B

50 A group of ten animals were fed the basal diet plus one percent sulfathiazole used in Example 2 to which had been added 2.0 grams of liver powder, 1:20 (containing 100 gammas of folic acid) per gram of sulfathiazole. At the end of 36 days, 55 eight of the ten animals had survived, those surviving having gained on the average 40 grams. An examination of the blood of the surviving animals showed on the average:

60 White cells, 15,200 per cubic millimeter
Granulocytes, 1,220 per cubic millimeter
Red cells, 7,600,000 per cubic millimeter
Hemoglobin, 12.6 grams per 100 milliliter
65 Hematocrit, 43.0 volume percent

Example 3

In a manner similar to Example 2, a diet containing one percent sulfanilamide was fed to a group of ten white rats. At the end of 56 days, 75 nine of the ten animals had survived, gaining an

average of 45 grams each. The average blood picture was:

White cells, 7,100 per cubic millimeter
Granulocytes, 430 per cubic millimeter
Red cells, 6,000,000 per cubic millimeter
Hemoglobin, 8.8 grams per 100 milliliter
Hematocrit, 29.0 volume percent

Example 3A

When 50 gammas of folic acid per gram of sulfanilamide was added to the diet of Example 3, all animals survived, and gained an average of 60 grams each. The average blood picture was:

White cells, 17,400 per cubic millimeter
Granulocytes, 2,440 per cubic millimeter
Red cells, 7,400,000 per cubic millimeter
Hemoglobin, 12.2 grams per 100 milliliter
Hematocrit, 40.0 volume percent

Example 3B

When 50 gammas of folic acid per gram of sulfanilamide, contained in 1000 milligrams of 1:20 liver powder, was added to the diet of Example 3, at the end of 56 days all animals had survived, gaining an average of 60 grams each. The average blood picture was:

White cells, 18,500 per cubic millimeter
Granulocytes, 2,590 per cubic millimeter
Red cells, 7,500,000 per cubic millimeter
Hemoglobin, 12.4 grams per 100 milliliter
Hematocrit, 39.0 volume percent

Example 4

To the basic diet of Example 1 there was added sulfadiazine one percent by weight. At the end of 56 days, ten of ten animals survived, having

Red cells, 7,600,000 per cubic millimeter
Hemoglobin, 9.8 grams per 100 milliliter
Hematocrit, 32.0 volume percent

Example 4B

5 To the diet of Example 4 there was added 100 gammas of folic acid per gram of sulfadiazine as 1.0 gram of dried 1:20 liver extract. Ten of ten animals survived the 56 days of feeding, gaining an average of 58 grams each. The average blood picture was:

White cells, 15,600 per cubic millimeter
Granulocytes, 1,400 per cubic millimeter
Red cells, 7,900,000 per cubic millimeter
15 Hemoglobin, 10.2 grams per 100 milliliter
Hematocrit, 40.0 volume percent

Example 4C

20 To the diet of Example 4 there was added 100 gammas of folic acid per gram of sulfadiazine as represented by 2.0 grams of dried yeast extract per 100 grams of diet. Nine of ten animals survived the 56 days of feeding, gaining on the average of 35 grams each. The average blood picture was:

White cells, 10,800 per cubic millimeter
Granulocytes, 1,300 per cubic millimeter
Red cells, 7,200,000 per cubic millimeter
Hemoglobin, 11.8 grams per 100 milliliter
30 Hematocrit, 42.0 volume percent

Example 5

To a basic diet as in Example 1, there was added in separate experiments (1) 0.5 per cent sulfadiazine and 0.5 percent sulfamerazine, and (2) the above quantities of sulfonamides and 750 gammas of folic acid per 100 grams of diet. At the end of 56 days the following results were noted:

	Red Cells per (mm.) ³	White Cells per (mm.) ³	Hemato- crit, Vol. Per Cent	Hemo- globin/100 cc.	Granulo- cytes per (mm.) ³
Basal Diet Only	8,390,000	12,870	44.7	13.6 g.	1,390
Diet plus 0.5% Sulfadiazine and 0.5% Sulfamerazine	6,060,000	7,740	31.8	10.0	380
Diet plus Sulfonamides plus Folic Acid 750 gammas per 100 grams diet	7,580,000	14,820	39.0	12.1	1,820

gained an average weight of 20 grams each. The 50 average blood picture was:

White cells, 8,300 per cubic millimeter
Granulocytes, 130 per cubic millimeter
Red cells, 5,900,000 per cubic millimeter
Hemoglobin, 8.1 grams per 100 milliliter
Hematocrit, 32.0 volume percent

Example 6

With a basic diet as in Example 1, the following supplements were added. After 56 days of feeding the red cell count, white cell count, 55 hematocrit value, hemoglobin and granulocytes were determined to be as follows:

	Red Cells per (mm.) ³	White Cells per (mm.) ³	Hemato- crit, Vol. Per Cent	Hemo- globin/100 cc.	Granulo- cytes per (mm.) ³
Basal Diet Only	8,940,000	12,460	46.1	13.7 g.	1,170
Basal Diet plus 0.33 per cent sulfathiazole, 0.33 per cent sulfadiazine, 0.33 per cent sulfamerazine	5,790,000	7,640	32.4	9.45	310
Diet with the following added per 100 grams of diet: 0.33% sulfathiazole, 0.33% sulfadiazine, 0.33% sulfamerazine, 1,000 gammas folic acid	7,900,000	15,700	39.6	12.2	1,600

Example 4A

To the diet of Example 4 was added 50 gammas of folic acid per gram of sulfadiazine. Nine of ten animals survived after 56 days of feeding, having gained an average of 40 grams each. The average blood picture was:

White cells, 12,500 per cubic millimeter
Granulocytes, 1,060 per cubic millimeter

70 Various modifications may be made in the present invention without departing from the spirit or scope thereof, and it is to be understood that we limit ourselves only as defined in the appended claims.

We claim:

1. A compressed tablet comprising about 167 milligrams of sulfadiazine, about 167 milligrams 75 of sulfamerazine, about 167 milligrams of dried

aqueous liver extract, and about 0.25 milligram of folic acid, said tablet upon oral administration producing effective blood levels of sulfadiazine and sulfamerazine without substantial injurious effect on blood cells and hemoglobin.

2. A therapeutic composition comprising about one part of sulfadiazine, about one part of sulfamerazine, about one part of dried aqueous liver extract, and about .0015 part of folic acid, said composition upon oral administration producing effective blood levels of sulfadiazine and sulfamerazine without substantial injurious effect on blood cells and hemoglobin.
